(57) **CLAIM**

The ornamental design for a drawer-type egg carton as shown and described.

DESCRIPTION

FIG. 1 is a front view of the drawer-type egg carton showing our new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines shown illustrate portions of the drawer-type egg carton and form no part of the claimed design.

1 Claim, 7 Drawing Sheets
